(57) **CLAIM**

The ornamental design for a vehicular on board diagnostics electrical connector, as shown and described.

DESCRIPTION

FIG. 1 is a top front perspective view of the vehicular on board diagnostics electrical connector of the instant invention; FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The portions of the figures illustrated in broken lines show unclaimed subject matter only and form no part of the claimed subject matter.
